UNITED STATES PATENT OFFICE.

YGE G. MULDER, OF ORANGE CITY, IOWA.

VETERINARY INSTRUMENT.

1,118,040.

Specification of Letters Patent. Patented Nov. 24, 1914.

Application filed April 6, 1914. Serial No. 829,823.

To all whom it may concern:

Be it known that I, YGE G. MULDER, citizen of the United States, residing at Orange City, in the county of Sioux and State of 5 Iowa, have invented certain new and useful Improvements in Veterinary Instruments, of which the following is a specification.

My invention relates to improvements in instruments for artificially or mechanically 10 impregnating female animals for breeding purposes, and the particular improvements which I have invented in this connection, have for their primary object, the production of a device that can be attached to 15 semen extractors of well-known form, and that will take the place of capsule filling and inserting operations which follow the extractor, as the art is now commonly practised.

20 Owing to exposure to the air and dust which occurs when the semen is inserted in capsules, a large percentage of the spermatozoa is rendered infertile, and this serious objection to the use of capsules is 25 avoided by my present invention which does not expose the semen to the chilling and other deleterious influence of the atmosphere which prevails where such operations are usually carried on.

30 Other objects of general utility are served by my invention, as will be apparent to those skilled in the art to which it relates.

I have illustrated a preferred adaptation 35 of my invention in the accompanying drawing, in which:

Figure 1, is an elevational view of a semen applicator constructed according to my invention: Fig. 2, is an enlarged longitudinal sectional view of the elements which constitute my improvements, superfluous portions 40 being broken off.

Referring to the details of the drawing, the reference numeral 3, represents a metal tube, the outer end of which has a curved 45 seat 3^a formed therein, and the opposite end of which is threaded as at 3^b, to adapt it to be screwed into the end of the extractor cylinder 10, the latter having the usual plunger 10^a, and being of well known construction and operation, so that it is not shown 50 in detail.

4 represents a metal tube, which for the major portion of its length, is of sufficiently greater cross-diameter than the tube 3 to 55 permit the insertion of a suitable non-conducting packing 4^b between the inner walls

of the tube 3 and the outer walls of the tube 4. The diameter of the tube 4 is reduced for a portion of its length, as at 4^c, and this reduced portion is externally threaded, as 60 at 4^d.

5, represents a valve which is normally seated in the end 3^a of the tube 3, and is loosely held upon its seat, by a weak spiral spring 6, which is held under desired compression by a cap 7 in which is a discharge opening 7^a, and said cap is internally threaded to engage the threads 4^d of the tube 4. Surrounding the portion 4^c of the tube 4, are washers 8, of fiber, rubber or 70 other suitable material to effect a substantially air-tight joint between the walls of the parts.

9 represents a glass sleeve which fits with a close but sliding fit around the cap 7, the washers 8 and the tube 4, and is provided with a discharge opening 9^a in its conical shaped outer end.

The operation or use of an instrument 80 constructed as above described, is as follows:—Assuming that the cylinder 10 has been supplied with semen in the usual manner, and its extractor tube or extension, (not shown) removed, and the tube 3 screwed in place, the plunger 10^a will be pushed in- 85 wardly to force a predetermined charge of semen into the glass sleeve 9, the ball-valve 5 being unseated sufficiently to allow the passage of the fluid into the interior of the sleeve. The operator then grasps the sleeve 90 with his right hand and inserts and holds it in the animal's uterus, and with his left hand pushes the tube 4 (with the cap 7) forwardly into the sleeve 9, thereby ejecting the semen from the latter into the 95 uterus, the incidental back-pressure upon the ball 5 holding it upon its seat and thereby preventing any of the semen from re-entering the tube 3.

It will be understood that the entire instrument will be heated to blood temperature before the extracting operation takes place, and that the fluid within the tube 3 will be protected or retarded from losing its heat by the heat in the instrument, and by the non-conducting properties of the packing 4^b.

As all the members which make up my improved applicator are readily separable, sterilization is easily effected.

It will be obvious that the transparent property of the sleeve 9 will permit the op-

erator to observe the quantity and condition of the charge of semen, and that by drawing out the sleeve relative to the cap, in the first instance, the capacity of the receiving chamber will be increased.

It will also be understood that when a charge of semen is forced into the sleeve, the operator will place his forefinger loosely over the orifice 9^a, so as to permit the air 10 to escape without loss of the impregnating fluid which will enter the sleeve as the air escapes.

I claim as my invention:—

- 15 1. In an instrument of the character described, in combination with a cylinder having a plunger therein, a tube adapted to be detachably connected with the discharge end of the cylinder, a valve seated in the discharge end of said tube, a tube surrounding said first named tube, a cap adjustably connected with said second tube and having a discharge opening therein, yielding means

bearing upon said cap and valve, and a sleeve slidably fitting said cap and second tube, said sleeve having a discharge opening at its outer end.

2. In an instrument of the character described, in combination with a cylinder having a plunger therein, a tube adapted to be detachably connected with the discharge end 30 of the cylinder, a valve seated in the outer end of the tube a second tube surrounding said first named tube and insulated therefrom, a cap adjustably connected with the outer end of the second tube and having a 35 hole therein, a spring bearing against said cap and valve, and a transparent sleeve slidably fitting said cap and second tube.

In testimony whereof I affix my signature in the presence of two witnesses.

YGE G. MULDER.
